UNITED STATES PATENT OFFICE.

RUDOLF LOEB, OF JENKINTOWN, PENNSYLVANIA.

GUIDE FOR FABRICS BEING HEMMED.

1,357,065.

Specification of Letters Patent. Patented Oct. 26, 1920.

Application filed February 25, 1920. Serial No. 361,143.

To all whom it may concern:

Be it known that I, RUDOLF LOEB, a citizen of the United States, residing in Jenkintown, Montgomery county, Pennsylvania, have invented certain Improvements in Guides for Fabrics Being Hemmed, of which the following is a specification.

The object of my invention is to provide a guide for fabric which has been hemmed on one side and which has to be hemmed or sewed at the opposite side of the material at a given distance from the hem.

The invention relates particularly to the hemming of handkerchiefs, and the present invention is used in connection with a machine for hemming a long piece from which are put the proper lengths to form the handkerchiefs, and it is essential that some means be provided for guiding the fabric to the sewing machine which will not need the constant attention of the operator.

In the accompanying drawings, Figure 1 is a perspective view illustrating my improved guide in connection with the hemmed edge of a handkerchief.

Fig. 2 is a sectional view of the guide.

Fig. 3 is an end view.

Fig. 4 is a plan view illustrating a modification in which a bar is used instead of a ball, and

Fig. 5 is a section on the line 5—5, Fig. 4;

Fig. 6 is a diagram view showing the roll of fabric and the relation of the guide to the needle and the sewing machine; and

Fig. 7 is a view showing the use of a plurality of guide balls.

"a" is the fabric; "b" is the tubular seam or hem, and "c" is the hem stitching. This construction may or may not be used, but a hollow hem must be formed at the edge of the fabric. I avail myself of this hollow hem on one edge of the fabric and place therein a ball 1, Fig. 2, and this ball is loosely confined in a carrier 2 consisting of a bottom plate 3 and a top plate 4 secured to the bottom plate by a screw 5 or other fastener. The two plates 3 and 4 are cut away to form a throat 6 and each plate is recessed—the lower plate being recessed at 7 and the upper plate at 8, directly above the recess on the plate 3 for the reception of the ball 1 and the fabric which incloses the ball. These recesses are of such a size as to allow the fabric to slide freely over the ball, but the ball is prevented from moving

out of the carrier so that as the fabric is moved in the direction of the arrow as the stitch on the opposite side is made, the ball acts as a guide for the fabric, so that the two hemstitched sides will be parallel. The 60 edges of the plates forming the throat are rounded as shown in Fig. 3, so that the fabric can readily pass through the throat.

In the present instance the upper plate 4 is held by a single screw 5 and the guide pin 65 9, although other means of fastening the two plates may be used if desired. In Fig. 4, I have illustrated a modification in which a rod 1^a is used in place of the ball, and this rod is rounded at each end, and the ends of 70 the rod are adapted to recesses 6^a forming a throat in the projections 10 of an elongated carrier 2^a. By this construction an elongated guide is provided. The rod may be 75 of any length desired.

As a substitute for this rod, where an extended guide is necessary, a plurality of balls 1^b may be located in a carrier 2^b, Fig. 7.

In referring to Fig. 6, "x" is a roll of 80 fabric used in the manufacture of handkerchiefs, and one edge "y" of this fabric has been hemstitched in a suitable machine for this purpose, and the other edge "z" is to be hemstitched. The ball 1 of the carrier 2 is 85 passed into the hem "b" at the edge "y" of the fabric and the guide is set in proper relation to the needle "d," of a sewing machine having a hemstitching attachment. The sewing machine is the ordinary power 90 driven machine, and the material is fed from the roll in any suitable manner. The guide 2 holds the edge "y" of the fabric in proper relation to the needle so that the entire roll can be hem-stitched on each side, 95 the two hems being equidistant apart throughout the entire roll.

While the invention is particularly adapted for use in hemming handkerchiefs, it will be understood that it can be used for guiding any fabric which has a hem.

I claim:

1. The combination of means for making a hem at one edge of a fabric including a needle, the other edge of which has been previously hemmed; with a guide located in the hem; and means for holding the guide in position in respect to the needle; said holding means allowing the free movement 105 of the fabric over the guide.

2. The combination of a carrier having a throat; a guide located in the throat and held against longitudinal movement; the guide being adapted to pass into a hem formed in the edge of the fabric to act as a guide for said fabric.
3. The combination in a carrier, of two plates cut away to form a throat, each plate having a recess; and a ball located in the recesses of the plates of a greater diameter than the height of the throat and less in di-

ameter than the recesses, said ball being adapted to enter the hem of a piece of fabric.

4. The combination with a carrier of two plates; a screw for securing the two plates together, each plate being shaped to form a throat, and recessed; the two recesses being one directly above the other; a ball located in the recess of the throat and adapted to enter the hem of the fabric.

RUDOLF LOEB.
